UNITED STATES PATENT OFFICE.

IRA B. HUMPHREYS, OF DENVER, COLORADO.

PUMPING MECHANISM.

Application filed February 24, 1923. Serial No. 620,913.

To all whom it may concern:

Be it known that I, IRA B. HUMPHREYS, a citizen of the United States, residing at Denver, in the county of Denver and State 5 of Colorado, have invented certain new and useful Improvements in Pumping Mechanism, of which the following is a specification, reference being had therein to the accompanying drawing.

10 This invention relates to improvements in pumping mechanisms and more particularly to a fluid operated pumping mechanism.

My improved pumping mechanism is particularly adapted for use in deep wells for 15 pumping water, oil or any other liquid therefrom. The present arrangement now used in deep wells is objectionable because of the fact that a rigid pump rod extending the entire depth of the well is the usual 20 form of pump mechanism and the use of a construction of this nature has many limitations, which includes speed and capacity, among other objections well known to those skilled in the art.

25 In my pumping mechanism the rigid pump rod construction is done away with by the use of a column of liquid under pressure which operates as the motive power to elevate the liquid to the point desired.

30 My improved pump is a double action pump for elevating liquids from deep wells to a suitable point above the well where it is delivered and among other features of construction consists of a pumping mecha-

35 nism which may be disposed in any suitable source of liquid supply such as a pipe or well and the actuating means may be situated in any convenient place, which may be remote from the well or pipe.

40 One of the objects of this invention is to provide a fluid operated pump to elevate fluid from a source of supply and to have the pump actuated from a remote point by fluid means.

45 Another object of the invention is to provide a pump for elevating liquid which is of small diametrical dimensions so that it will be adapted to be disposed in a source 50 of liquid supply such as a well or pipe and to actuate the pump from a remote point by a liquid or fluid means under pressure.

Another object of this invention is to provide a double acting fluid operated pump for elevating fluids and to operate the pump 55 by a fluid under pressure from a remote point.

Another object of the invention is to provide a combined hydraulic pump and engine having the engine exhaust and pump discharge through the same channels. 60

Another object of the invention is to provide a device of the character described having only one inlet and one outlet pipe or channel.

A still further object of the invention is 65 to provide a combined double acting hydraulic pump and engine having only two working valves.

A further object of the invention is to provide a combined hydraulic pump and 70 engine using part of the fluid pumped as a fluid operating or actuating medium.

A further object of the invention is to provide a novel means for reversing the direction of movement of the pump piston. 75

A still further object of the invention is to provide a novel means for throwing the device off of dead center should the same ever assume this position.

In the drawings:

Figure 1 is a vertical sectional view of my improved pumping mechanism, the inlet and outlet pipes at the top of the device being shown in side elevation, and the operating parts of the mechanism being 85 shown at the top of the upward stroke of the pump piston.

Fig. 2 is a vertical sectional view of my improved device the operating parts of the device being shown at the end of the downward stroke of the pump piston. 90

Fig. 3 is a vertical sectional view showing the control valve and the working valve in the positions they assume just prior to the reversing of the direction of movement of the pump piston, the positions they assume after the reversing of the movement of the pump piston being shown in dotted lines. 95

Fig. 4 is a vertical sectional view of the same parts shown in Fig. 3, the control valve and working valve being shown in a position which I have termed as dead center while in dotted lines the parts are shown in an extended position which they assume when the device is forced off the dead center so that it will be operative. 100

Fig. 5 is a conventional showing of a high-pressure pump, such as may be utilized for delivering fluid under high pressure to the inlet pipe 10 of the pumping mechanism. 110

The drawings show an operative structure of my improved pumping device but I

desire it to be understood that many minor changes of construction could be made in the particular adaptation shown in these drawings without departing from the spirit of the invention.

Throughout the description of the drawings similar parts are designated by like reference numerals, A representing the side walls of a well or well casing, B representing the outlet pipe or casing of the pumping mechanism, C representing the inlet or high pressure pipe or casing. D represents the control valve housing in which the control valve E is adapted to reciprocate to effect a movement of the working valve F. G designates the plunger rod which carries the working or pump piston H which is adapted to reciprocate the pump plunger J within the pump plunger cylinder or chamber K. The piston barrel or cylinder is designated at L.

Attention is called to the fact that the pump mechanism shown in the drawings is to such a small scale that it has been difficult to set the invention forth clearly. From the top of the control valve housing D to the bottom 49 of the outlet pipe B is approximately 35 feet in distance. To show an assembled view of the device it has been necessary to break through the sectional views to shorten the same in order that they might be put on a sheet of drawing in assembled position.

It will be readily understood that my pumping mechanism which includes the parts B to L inclusive, together with their supplemental parts, are lowered within the well or well casing A until the same are completely submerged in the fluid in the well casing. In a deep well it will therefore be understood that the discharge pipe or casing B and the inlet high pressure pipe or casing C runs the entire depth of the well and extends from the top of the well to any point desired. Should it be desired, the pumping mechanism can be lowered until the same is resting upon the bottom of the well or pipe A.

The top end of the inlet pipe C is designated at 10 and is to be connected to any desirable form of pump or power plant or pump such as disclosed in Fig. 5 of the drawing which will force liquid at high pressure down the pipe. The upper end of the discharge pipe B is designated at 11 and runs off as at 12 to any desired point where the same may empty into a tank 100 or the like. It will be seen that the top end 10 of the inlet pipe C extends through the top end 11 of the discharge pipe B through suitable packing 13 or the equivalent. The particular manner of branching the top end of the inlet and outlet pipes away from each other forms no particular part of this invention and therefore the de-

scription of this feature is dealt with only broadly.

It is important however to have means of communication, preferably above the well, between the upper ends of the inlet and outlet pipes and I have provided this communication in the form of a pipe 14 which joins them, as clearly appears in Fig. 1 of the drawings. The top end 10 of the inlet pipe C is provided with a valve 15 at a point below that where the pipe 14 enters. The branch 12 of the outlet pipe B is provided with a valve 16 at a point beyond that where the pipe 14 enters this branch. The connecting pipe 14 is provided with a valve 17 at a point intermediate its ends. The purpose of this construction will be described later.

As previously mentioned the outlet pipe B extends down the well or casing A and in reality with its continuations forms the outer shell or casing of the entire pumping mechanism. The inlet pipe C which is of a smaller diameter than that of the outlet pipe extends down the outlet pipe to a point 25 where it is screw-threadedly or otherwise suitably attached to an extension pipe or housing 26 which, as clearly appears, has an open top 24 and has very thick walls, one of which is provided with a high pressure inlet port or opening 27 communicating with a downwardly extending channel 28 which I have termed the working valve cylinder and is provided at its lower end with a high pressure outlet port 29. At a point below the channel or working valve cylinder 28 and in the same wall of the pipe or housing 26 is another downwardly extending channel 30 having ports 31 and 32 at its upper and lower ends respectively.

The inner lower end of the pipe or housing 26 is closed by a bottom 33 while the space between the housing 26 and the outlet pipe B is closed by a circumferential web or collar 34 positioned adjacent the bottom of the housing and stops all down flow in the pipe B at this point. Communication between the housing 26 and the outlet pipe B above the web 34 is had through two separated discharge outlet ports 35 and 36. Communication between the housing 26 and the outlet pipe B below the web 34 is had by means of the channel 37 having ports 38 and 39 at its upper and lower ends respectively. The communication between the housing 26 and the continuation 26^a of the said housing which I have termed the plunger rod packing case is had around the bottom 33 of the housing 26 through the before mentioned channel 30 having ports 31 and 32 at its ends.

The plunger rod packing case 26^a which, of course, is cylindrical in cross-section, terminates in an inwardly extending circumferential shoulder or collar 40 carrying any suitable packing or packing rings 40^a.

This circumferential shoulder 40 of the case 26^a in reality ends the inner pipe or casing C. The continuation of flow of the fluid in this pressure pipe C is had through openings 41 which I have termed plunger ports inasmuch as they are in the top of the plunger rod G.

The plunger rod G is hollow as at 42 and the upper end of this rod reciprocates in the plunger rod packing case 26^a the walls of the plunger rod engaging of course the packing 40^a of the case. The plunger rod G is provided with a piston H intermediate its ends and this piston is adapted to reciprocate within the outlet pipe B or the working barrel L between the bottom 33 of the case 26^a and the inwardly extending circumferential shoulder or flange 43 of the pipe B. The piston H is provided with suitable packing or packing rings 44 which engage the inner side of the outlet pipe B while the circumferential shoulder 43 of the outlet pipe is provided with suitable packing 45 which engages the outer face of the plunger rod extension below the piston H. The plunger rod is provided with suitable ports 46, which I have termed the working barrel ports, positioned below the piston. These ports provide communication between the hollow plunger rod and the outlet pipe B intermediate the piston H and the circumferential shoulder 43, which is in fact the working barrel or cylinder and is designated at L.

As clearly appears in the drawings the plunger rod continues past the circumferential shoulder 43 of the outlet pipe B and carries on its lower end the pump plunger J which is provided with suitable packing or packing rings 47 which engages the wall of the outlet pipe B. The plunger rod is open at its bottom and is provided with any suitable ball-valve 48 or its equivalent. It will be readily understood that if it should be desirable a double ball valve could be used in place of the single valve shown. No particular description is given of this valve as many of the well known valve constructions could be utilized in the place of the particular simple valve construction shown in the drawings.

The outlet pipe B terminates in a bottom 49 having an opening 50 provided with any suitable form of ball-valve 51 or its equivalent.

The space between the bottom 49 of the outlet pipe B and the shoulder or flange 43 constitutes the pump cylinder K and in the particular pump shown here in the drawings it is intended that this cylinder be of sufficient depth to allow a five foot stroke of the pump plunger. The pump chamber K is provided with breather ports 52 in communication with the well or well casing A and these ports are located imme-

diate below or adjacent the circumferential shoulder 43 of the outlet pipe B.

As this pumping device is using a fluid column as a motive power it is necessary to have certain valve arrangements whereby the motive power is directed in the proper channels and it is also necessary to have means for directing the motive power to cause a reversal of the movement of the pump piston and plunger. I will now take up the description of the reversing mechanism and of the valves used to control and direct the flow of the fluid motive power.

I have previously spoken of the control valve housing D and in connection with this housing it is noted that the same is supported within the extension pipe or housing 26 of the inlet pipe C by means of an outwardly extending circumferential flange 53 supported upon an inwardly extending shoulder 54 of the housing 26. The control valve housing is provided at its lower end with a bottom 55 having a central opening therein and the housing is further provided intermediate its top 56 and its lower end with an inwardly extending circumferential shoulder 57 having an opening therein. Communication between the chamber 58, which is located between the bottom 55 and the shoulder 57 of the housing, and the inlet pipe C is had through an inlet port 59 which I have termed the control valve inlet port. The valve housing is provided with another chamber 60 between its top 55 and its circumferential shoulder 57. The chamber 60 of the valve housing D is in communication with that portion of the housing 26 below the lower end of the valve housing D through the medium of a channel 61.

The control valve E which causes the reversing of the direction of the movement of the pump piston and plunger is adapted to reciprocate within the control valve housing D and is guided in this reciprocation by the openings in the valve housing bottom 55 and shoulder 57. Intermediate the ends of the control valve E is a circumferential outwardly projecting flange or piston 62 which limits the movement of the valve as the bottom 55 and shoulder 57 of the housing limits through contact the movement of this piston 62. The control valve E is further provided with an exhaust port 63 above the piston 62 and an exhaust port 64 below the piston 62. In certain positions of the valve, which will be hereinafter described, these ports function in a material manner in respect to the functioning of the control valve.

The extension of the valve E below the control valve housing D is represented at 65 and I have termed the same the working valve rod for the reason that this extension or rod is the actuating means for a part of the movement of the working valve F here-

tofore spoken of. This working valve rod 65 is hollow as at 66 to receive the control valve rod 67 which is provided at its upper end with an enlarged head 68 and is attached 5 at its lower end 69 to the top of the pump plunger rod G.

Although a rigid connection between the control valve rod 67 and the plunger rod G is shown it is desired to call attention to 10 the fact that a universal connection might be preferable between these rods to allow some latitude of horizontal movement between them to take care of and prevent any wedging of the control valve rod where it passes through the bottom 33 of the housing 26 and the bottom 70 of the working valve rod 65. A packing 71 is shown at the point where the control valve passes through the bottom 33 of the housing 26.

20 Adjacent its bottom the working valve rod 65 is provided with an outwardly extending circumferential flange 73 while intermediate this flange and the top 74 of the working valve rod is another circumferential flange 25 75.

The working valve F surrounds the working valve rod 65 intermediate the two flanges 73 and 75 just mentioned and has at its bottom an outwardly extending circumferential flange 76 and at its top an outwardly extending circumferential flange 77, these flanges being provided with suitable packing 78 for engaging the inner face of the housing 26. As the working valve rod 65 is moved upwardly and downwardly its flanges 73 and 75 engage the working valve and move it into different positions, the purpose of which will be hereinafter described. The extreme upward movement of the working 30 35 valve F is limited by the internal shoulder 79 of the housing 26. This extreme upward movement of the valve is not the top of its normal working movement but is only assumed by the valve when the device has been forced or carried off center, as will be hereinafter described.

Attention is directed to the fact that it might prove advisable to provide the piston 62 of the control valve E with some form of 50 packing and I have found it preferable to use in this instance what is commonly known as a labyrinth packing as this form of packing will not add any material friction to be overcome in the movement of the valve and proves sufficiently tight.

Operation.

Having described the component and co-operating parts of my improved pumping mechanism I will now take up and describe the operation of the device.

In Fig. 1 of the drawings I have shown the pumping mechanism, at the top of the upward stroke of the piston.

65 With the parts in the positions shown in

Fig. 1 fluid at high pressure is being forced down through the top 10 of the inlet pipe C from some suitable supply such as a hydraulic pump. This high pressure fluid or fluid column enters the open top 24 of the 70 housing 26. The major portion of this fluid enters the channel or working valve cylinder 28 through its upper port 27 and continuing down this channel the fluid passes outwardly through the lower port 29 into 75 the working valve F. The fluid circulates around this valve and finds its outlet through the port 38 down the channel 37 and into the piston barrel chamber or cylinder L through the port 39. The fluid then 80 strikes the piston H and drives the same downwardly. As the piston H is driven downwardly the pump plunger J displaces the liquid in the pump cylinder K. It will be readily understood of course that the 85 valve 51 of the pump cylinder closes and the valve 48 of the pump plunger opens as the pump plunger descends. The liquid in the pump cylinder is therefore displaced upwardly into the hollow pump plunger rod 90 G and through the plunger ports 41 in the top of the plunger rod into the plunger rod packing case 26. The liquid finds its way from this casing upwardly through the channel 30 into the housing 26 from whence it escapes through the lower discharge port 36 into the discharge pipe or casing B. The fluid then travels up the outlet pipe B and through its top 11 and branch 12 to any suitable point of delivery.

Attention is directed to the fact that as the pump plunger and piston descend, the liquid in the piston barrel intermediate the piston H and the bottom or flange 43 of the barrel is displaced or exhausted into the hollow pump plunger through the working barrel ports 46 and joins the outlet flow of liquid.

As the piston and pump plunger and plunger rod descend, it is obvious that the control valve rod 67 also descends as it is attached to the top of the pump plunger. When the piston has reached a point approximately at the bottom of its stroke the head 68 of the control rod engages the bottom 70 of the working valve rod 65 and pulls this rod downwardly together with the controlling valve E which is an integral part of the working valve rod 65.

A continued downward movement of the piston pulls the controlling valve and the working valve rod to the positions shown in Fig. 3 of the drawings. Attention is called to the fact that as yet the working valve F has not moved.

As liquid under pressure is always in the inlet pipe C, liquid under pressure likewise surrounds the control valve housing D which is situated in the housing 26 which is in fact a continuation of the inlet pipe.

Therefore when the parts are in the positions shown in Fig. 1 high pressure liquid enters through the control valve port 59 into the chamber 58. With the control valve in the position shown in Fig. 1 this high pressure being under the control valve piston 62 holds this valve against the upper shoulder 57 of the control valve housing.

When the pressure on the top of the piston 10 ton H has pulled the parts to the positions shown in Fig. 3, just described, the piston 62 of the control valve E is just opposite the control valve inlet port 59 and as this piston is of slightly less width than the inlet port 15 opening 59 a leakage of high pressure fluid is had through this port into the chamber 58. This leakage is on both sides of the piston 62 of the valve and finds escape through the exhaust ports or channels 63 and 64 20 above and below the piston respectively.

As high pressure fluid is still working against the top of the piston H the control valve rod 67 is still pulling the control valve E downwardly and the instant that the piston 25 62 of the valve assumes a position to close the leakage through the inlet control 59 below the piston the high pressure coming through this port is concentrated entirely upon the upper side of the valve piston. This continued downward movement 30 of the valve has closed the exhaust port 63 above the valve piston and so the pressure above the piston can not escape while that below the piston can exhaust through the port 64. The result is that the control valve 35 E is driven by the high pressure in a very rapid movement downwardly to the limits of its movement in this direction, which is shown in dotted lines in Fig. 3.

40 In the meantime the flange 75 of the working valve rod 65 has engaged the top of the working valve F and when the control valve E together with its integral part, the working valve rod 65, is driven downwardly by the high pressure the working valve F is likewise carried downwardly to the position shown in dotted lines in Fig. 3.

It will now be seen that the parts are in the positions shown in Fig. 2 of the drawings 50 and that the movement of direction of the piston H is about to be reversed because the channel 37 which permits the flow of high pressure fluid out of the housing 26 against the top of the piston H has been closed by the movement of the working valve F. The movement of the working valve F in closing the channel 37 has opened the port 31 of the channel 30 and now permits the high pressure fluid coming down 55 the inlet pipe C and the channel or working valve cylinder 28 to flow through the port 32 of the channel 30 into the housing 26^a above the top of the pump cylinder G. This chamber 26^a now becomes a high pressure 60 chamber or inlet chamber while on the

downward stroke of the piston H this chamber was a low pressure or outlet chamber. The high pressure escapes from the chamber or housing 26^a into the hollow pump plunger rod G through the ports 41 and from the 70 interior of the pump plunger rod the high pressure flows outwardly through the working barrel ports 46 into the working barrel or piston cylinder L at a point below the piston H and above the bottom or 75 shoulder 43 of this barrel or chamber.

The high pressure liquid or column is now exerting an upward force beneath the piston H and the piston will therefore start upon its upward stroke or movement, a complete reversal of the direction of the movement of the piston having now been completed through the medium of the control and the working valve directing the flow 80 of the high pressure fluid.

As the piston H ascends the liquid, which is now low pressure liquid, in the working barrel L above the piston is displaced upwardly and outwardly from the top of this barrel through the channel 37 and into the 85 housing 26 at a point above the working valve F. The fluid escapes from this housing through the upper discharge outlet port 35 into the main discharge pipe B and is 90 delivered to a point above the well or source 95 of supply.

It will be readily apparent that as the pump plunger J ascends its ball valve 48 will close and a suction will be created in the plunger cylinder K which will cause 100 liquid from the well to be drawn upwardly into this cylinder, lifting the valve 51 as it enters. As the plunger J ascends it will exhaust the liquid above it in the cylinder 105 through the breather ports 52 out into the well or casing A.

Attention is directed to the fact that the discharge outlet port 35 discharges pumped liquid on the upward stroke of the piston and that the discharge outlet port 36 discharges pumped liquid on the downward stroke of the piston and that both of these ports are located in the wall of the housing 26 at a point above the web or bottom 34 of the housing 26 which forms a bottom for 110 115 the main outlet pipe or casing B.

As the piston H ascends in addition to discharging fluid it lifts the control valve E to the position shown in full line in Fig. 3 through the medium of the control valve rod 120 67 and its top 68 which engage the top 74 of the working valve rod.

When the piston 62 of the control valve E is lifted to a position so that its piston 125 62 stops the flow of high pressure fluid into the chamber 58 above this piston the high pressure will get in the chamber below the piston of the valve and drive the valve upward to the position shown in Fig. 1 of the drawings and at the same time carry the 130

working valve F upwardly to the position shown in this figure of the drawing, due to the fact that the flange 73 of the working valve rod will engage and lift the working valve.

With the parts again in the positions shown in Fig. 1 of the drawings the direction of movement of the piston will be reversed and it will be driven downward to the bottom of its stroke which is shown in Fig. 10 of the drawings. This operation will be carried on in endless rotation so long as high pressure fluid is supplied down the inlet pipe C and of course so long as high pressure fluid is provided the pump will discharge fluid through the outlet pipe B in an amount much in excess to the amount of fluid pumped into the device at high pressure.

20 *On-center position.*

In Fig. 4 I have shown in full lines a position of the control and working valves which I have termed an on-center position. I do not believe it is possible for the parts 25 to assume the positions shown in this figure of the drawings but if by some chance or mishap the valves should stop in the positions shown the device will be inoperative as all the high pressure ports communicating 30 with the piston are closed.

It is an essential attribute to a pumping mechanism which is many hundreds of feet down in a well, to be provided with some means to overcome an on-center position 35 should such a position of the parts ever occur. A great loss of time and money besides a great expenditure of effort would be necessary to pull the pumping mechanism, together with the many hundreds of feet of 40 inlet and outlet casing pipe, out of the well to get the pumping mechanism off center.

I have therefore provided a way to overcome the dead-center position should it occur and will now proceed to describe this 45 dead-center position and the means for overcoming it.

An examination of the positions of the control valve E and the working valve F as 50 shown in full lines in Fig. 4 will disclose that the control valve piston 62 is in such a position in respect to the high pressure inlet port 59 that an equal amount of high pressure is on either side of the piston head in the chamber 58, thus equalizing and holding 55 the control valve in the position shown.

This figure of the drawings discloses that the working valve F has closed the inlet ports of both the high pressure channels 30 and 37 so that no high pressure fluid can 60 get out of the housing 26 into the working barrel L or the hollow pump plunger G. An equal amount of high pressure fluid is working on the upper and lower flanges 77 and 76 respectively of the working valve F and 65 therefore this equalized pressure holds the

working valve in the position shown in this figure of the drawing.

In addition the controlling valve rod head 68 is in a position to be inoperative to move either the control valve E or the working valve F. It now becomes necessary to effect a movement of either the control valve or the working valve to allow the escape of high pressure fluid from the housing 26 so that it will operate upon the pump piston 75 H to move the same either upwardly or downwardly and thus start the operation of the pumping mechanism.

To bring about a movement of these valves I have provided the upper end 10 of 80 the high pressure inlet pipe C with a valve 15, the upper branch 12 of the outlet pipe B with a valve 16, and the pipe 14 which joins these two pipes with a valve 17.

In the normal operation of the device the 85 valves 15 and 16 are open and the valve 17 closed which allows a continuous inward flow in the inlet pipe and an outlet flow in the outlet pipe. By closing the valves 15 and 16 and opening the valve 17 the high 90 pressure fluid is diverted from the inlet pipe to the outlet pipe through the medium of their joining connection pipe 14 and the high 95 pressure fluid will transmit its pressure down the outlet pipe B surrounding the housing 100 26 and being stopped by the bottom or web 34 which extends outwardly from the housing 26, this pressure will enter the housing 26 through the upper exhaust outlet port opening 35 and will exert a pressure upon 105 the bottom 55 of the control valve housing D and raise this housing until its bottom strikes the piston 62 of the control valve. The housing will continue its upward movement carrying with it the control valve E 110 and its integral part the working valve rod 65. As the valve rod 65 ascends its lower flange 73 will engage the working valve F and carry the working valve upward.

The control valve housing D, the control 115 valve E and the working valve F will continue in their upward movement until the top or flange 77 of the working valve engages the internal shoulder 79 of the housing 26 which acts as a stop, at which time 120 the parts will be in the positions shown in dotted lines.

One intermediate point in the upward movement of the control valve housing is shown in dotted lines and when the valve 125 housing is in this position the piston 62 of the control valve will be in engagement with the bottom 55 of its housing. The upper-most dotted line position of the control valve housing D is the position it will assume when the top flange 77 of the working valve has engaged the internal shoulder 79 of the housing 26.

When the valves and parts are in the positions shown in the upper-most dotted lines 130

the pumping mechanism becomes operative as the channel 37 is now in communication with the high pressure fluid at its upper end and the piston barrel above the piston at its lower end. It remains now merely to open the valves 15 and 16 of the inlet and outlet pipes and to close the valve 17 of their connecting pipe 14 at which time the high pressure will be again thrown into the inlet pipe

10 C and as it comes down the same will strike the control valve housing D and drive the same down until it is seated upon the internal shoulder 54 of the housing 26. When this downward movement of the control 15 valve housing has taken place the parts of the device are in the positions shown in Fig. 2 of the drawings and the piston is receiving high pressure fluid which is causing it to make a downward stroke.

20 Attention is directed to the fact that when the high pressure is diverted from the inner pipe A to the outer pipe B for the purpose of carrying the pumping mechanism and its valves from an off-center position 25 that the valve housing D will necessarily displace a certain amount of fluid in the inner pipe A as this valve housing rises. To take care of this displaced liquid I have provided a by-pass pipe 100 which connects 30 with the inner pipe A at a point below the valve 15 and connects with the outlet pipe 12 at a point beyond the valve 16. This by-pass pipe is provided with a valve 101. It will be readily apparent that when the high 35 pressure is to be turned into the outer pipe B that the valve 101 of the by-pass pipe will be opened and when the high pressure causes the valve housing D to rise the displaced liquid above this housing in the pipe A will 40 find outlet through the by-pass pipe 100 into the outlet pipe 12 at a point beyond the valve 16 of the outlet pipe.

45 From the foregoing descriptions of the device and its operation it will be seen that my device is in reality a combined hydraulic engine and pump inasmuch as the piston H of the pumping mechanism acts as an engine piston and a pump piston for displacing the liquid upwardly through the discharge pipe.

50 Another peculiarity of the device is that the engine exhausts the high pressure into the pump delivery pipe and thereby displaces some of the liquid which is pumped through the outlet pipe and that the hollow 55 pump rod G acts alternately as a pump discharge and a high pressure inlet and in addition acts simultaneously as a pump discharge and engine exhaust.

60 I believe another peculiar and novel feature of my device is that the same has only two valves and that it has only one inlet and one outlet pipe. The advantage of the use of only one inlet and one outlet pipe has been previously stated as a necessary 65 attribute to the device because my pumping

mechanism must necessarily have a small diametrical dimension to allow its being lowered into a well or well casing or some similar source of liquid supply.

It is believed that it will be readily understood that my device operates upon differential fluid pressures.

Having thus described my invention what I desire to claim and secure by Letters Patent is:

75 1. A pumping apparatus of the class described comprising an inner and an outer pipe, the inner pipe an inlet pipe and the outer pipe an outlet pipe, a pumping mechanism embraced within the pipes, and a 80 pressure mechanism for constantly supplying fluid under pressure to the inlet pipe, for the purpose described.

2. A pumping apparatus of the class described comprising an inner and an outer pipe, a pumping mechanism embraced within the pipes, a pressure mechanism communicating with one of said pipes at a point above the said pumping mechanism, and the pressure selectively in communication with 90 the inner and outer pipes surrounding the pumping mechanism.

3. A pumping apparatus of the class described comprising an inner and an outer pipe, a pumping mechanism embraced within the pipes, the pumping mechanism being provided with a hollow plunger rod provided with a piston, a pressure mechanism communicating with one of said pipes at a point above the pumping mechanism, and the pressure alternately in communication with the interior and exterior of the pump plunger rod, for the purpose described.

4. A pumping apparatus of the class described, comprising an inlet and an outlet pipe, a pumping mechanism embraced within the pipes, the pumping mechanism provided with a hollow plunger rod provided with a piston, a pressure mechanism communicating with one of said pipes at a point above the pumping mechanism, and means within the pumping mechanism whereby the pressure is alternately directed above and below the plunger rod piston, for the purpose described.

110 5. A pumping apparatus of the class described comprising an inner and an outer pipe, a pumping mechanism embraced within the pipes, a pressure mechanism communicating with one of said pipes at a point above the said pumping mechanism, and means within the pumping mechanism to selectively direct the pressure from the inner to the outer pipes of the pumping mechanism.

115 6. A pumping apparatus of the class described, comprising an inner and an outer pipe, a double acting pumping mechanism embraced within the pipes, and a pressure mechanism in communication with one of 130

said pipes at a point above the said pumping mechanism, for the purpose described.

7. A pumping apparatus of the class described, comprising an inner and an outer pipe, a pumping mechanism carried by said pipes, a pressure mechanism communicating with one of said pipes at a point above the said pumping mechanism, a plunger rod, a piston for the pumping mechanism carried by said plunger rod, and reciprocating means within the pumping mechanism for alternately directing the pressure above and below the piston for the purpose described.

8. A pumping apparatus of the class described, comprising an inner and an outer pipe, a pumping mechanism embraced within the pipes, a pressure mechanism communicating with one of said pipes at a point above the said pumping mechanism, the upper and lower portions of the outer pipe surrounding the pumping mechanism closed against direct communication with each other, and means within the pumping mechanism to selectively direct the pressure from the inner pipe to the lower portion of the outer pipe, whereby the lower portion of the outer pipe is alternately an inlet and an outlet pipe.

9. A pumping apparatus of the class described, comprising an inner and an outer pipe, a pumping mechanism embraced within the pipes, a pressure mechanism communicating with one of said pipes at a point above the said pumping mechanism, and reciprocating means within the pumping mechanism for directing the course of the pressure to alternately raise and lower the pump, said reciprocating means actuated through a portion of its travel by the pumping mechanism and the remainder of its travel through the medium of the pressure.

10. A pumping apparatus of the class described, comprising an inner and an outer pipe, a pumping mechanism embraced within the pipes, a pressure mechanism communicating with one of said pipes at a point above said pumping mechanism, and means within the pipes below the pressure mechanism comprising two reciprocating valves whereby the pressure is directed to alternately raise and lower the pumping mechanism, for the purpose described.

11. A pumping apparatus of the class described, comprising an inner and an outer pipe, a pumping mechanism embraced within the pipes, a pressure mechanism communicating with the pumping mechanism, and means within the pumping mechanism whereby the pressure is directed to alternately raise and lower the pumping mechanism, whereby the device operates upon differential pressures.

12. A pumping apparatus of the class described comprising an inner and an outer pipe, a pumping mechanism embraced with-

in the pipes, a pressure mechanism communicating with one of said pipes above the said pumping mechanism, two valves for controlling both the inlet and outlet flows of the pumping mechanism, and the pump adapted to deliver liquid on both upward and downward strokes.

13. A pumping apparatus of the class described comprising an inner and an outer pipe, a double acting pumping mechanism embraced within the pipes, and a pressure mechanism communicating constantly with the inner pipe above the said pumping mechanism, for the purpose described.

14. In a pumping apparatus of the class described, comprising an inner and an outer pipe, a pumping mechanism provided with a hollow plunger rod carrying a piston, a pressure mechanism communicating with one of said pipes above the said pumping mechanism, means for alternately directing the pressure to the interior and exterior of said hollow plunger rod whereby the pressure is alternately directed above and below the pump piston, and the pumping mechanism constructed so that the pump piston discharges alternately directly through the outer pipe and through the hollow plunger into the outer pipe, whereby the plunger rod acts alternately as a pump discharge and a high pressure inlet, for the purpose described.

15. In a pumping apparatus of the class described comprising an inner and an outer pipe, a pumping mechanism embraced within the pipes, a pressure mechanism communicating with one of said pipes at a point above the said pumping mechanism, a piston for the pumping mechanism, valves for directing the course of the pressure, and the valves so arranged that a leakage of fluid acts as a displacement medium.

16. A pumping apparatus of the class described, comprising a hollow plunger rod provided with a piston, the plunger rod adapted to act alternately as a pump discharge and a high pressure inlet, a pressure mechanism communicating with said pumping mechanism, means to alternately direct the pressure above and below the piston, whereby the pumping mechanism acts as a combined hydraulic pump and engine.

17. A pumping apparatus of the class described, comprising a pumping mechanism, a pressure mechanism communicating with said pumping mechanism, a piston for the pumping mechanism, a hollow pump plunger rod for the piston, the plunger rod adapted to act alternately as a pump discharge and a high pressure inlet, a high pressure inlet conduit, a low pressure discharge conduit, the plunger rod having openings below the piston, and means to alternately direct the high pressure above and below the piston, whereby the pumping mechanism

acts as a combined hydraulic pump and engine having the engine exhaust and the pump discharge through the same pipe.

18. A pumping apparatus of the class described comprising an inner and an outer pipe, a pumping mechanism embraced within the pipes, a pressure mechanism communicating with the inner pipe at a point above the said pumping mechanism, and means to divert the pressure from the inner to the outer pipe at a point above the said pumping mechanism, for the purpose described.

19. A pumping apparatus of the class described comprising an inner and an outer pipe, a pumping mechanism embraced within the pipes, a hollow pump plunger rod provided with a piston, a housing above the plunger rod containing a pair of valves, a pressure mechanism communicating with the inner pipe at a point above the pumping mechanism, the valve housing and pumping mechanism in communication, and the valves and plunger rod operatively connected whereby the pressure will be directed from the valve housing alternately internally and externally to the plunger rod.

20. A pumping apparatus of the class described, comprising an inner inlet pipe and an outer outlet pipe concentrically arranged, a pumping mechanism embraced within the pipes, a pressure mechanism communicating with the inlet pipe at a point above the said pumping mechanism, a hollow pump plunger rod provided at its bottom with a plunger and intermediate its ends with a piston, a cylinder for the plunger, a cylinder for the piston, means to alternately direct the pressure into the hollow plunger and into the piston cylinder whereby the piston cylinder and the hollow plunger rod alternately serve as discharge pipes for the fluid displaced by the plunger and the piston.

21. A pumping apparatus of the class described, comprising an inner inlet pipe and an outer outlet pipe concentrically arranged, a pumping mechanism embraced within the pipes, a pump plunger rod provided with a pump plunger and a piston, a control valve and a working valve operatively connected, a pressure mechanism communicating with the inner pipe at a point above the pumping mechanism, a connection between the pump plunger rod and the valves whereby the valves are moved a predetermined distance by the movement of the pump plunger rod, and the control valve adapted to be operated at a predetermined time by the pressure, for the purpose described.

22. A pumping apparatus of the class described, comprising an inner and an outer pipe, a pumping mechanism embraced within the pipes, a pressure mechanism communicating with one of said pipes, a piston and a hollow plunger rod, and the pressure alternately in communication through the

plunger rod with the lower side of the piston and alternately around the plunger rod with the top of the piston.

23. A pumping apparatus of the class described, comprising an inner and outer pipe, a pumping mechanism embraced within the pipes, a pressure mechanism communicating with one of said pipes, a pump cylinder, a piston, a hollow pump plunger, and the pressure alternately in communication directly with the pump cylinder and with the hollow plunger.

24. A pumping apparatus of the class described, comprising an inner and an outer pipe, a double acting pumping mechanism carried thereby and forming said pipes into an inlet and outlet passage, a pressure mechanism communicating with the inner pipe at a point above the said pumping mechanism, the pumping mechanism provided with a piston, and means to direct the pressure to alternately raise and lower said pump piston.

25. A pumping apparatus of the class described comprising an inlet and an outlet pipe, a pumping mechanism provided with a piston, a pressure mechanism communicating with one of said pipes, and hydraulically operated means within the pumping mechanism whereby the pressure is alternately directed above and below the pump piston, for the purpose described.

26. A control valve for a pumping apparatus, comprising an elongated valve rod adapted for engagement with another valve, a piston for the control valve, a housing for the piston, and means to reciprocate the valve piston within the housing, for the purpose described.

27. In a device of the character described, a control valve, a working valve, a housing for the control valve and a housing for the working valve, the valves in operative engagement, and means to actuate the control valve, whereby the valves operate as and for the purpose described.

28. In a device of the character described, a control valve and a working valve operatively connected, separate housings for the valves, the connection between the control valve and the working valve having a lost motion movement, and means to actuate the control valve, for the purpose described.

29. A pumping apparatus of the class described, comprising an inner and outer pipe, a pumping mechanism embraced within the pipes, a pressure mechanism communicating with one of said pipes, a piston for the pumping mechanism, a hollow pump plunger rod, a cylinder for the piston, communication between the piston cylinder and the hollow plunger at a point below the piston, whereby the piston is cushioned at the bottom of its downward stroke.

30. A pumping apparatus of the class de-
